UNITED STATES PATENT OFFICE.

HELEN TOMIC, OF SOUTH BETHLEHEM, PENNSYLVANIA.

SALVAGE-INDICATING BUOY.

Application filed May 9, 1925. Serial No. 28,994.

To all whom it may concern:

Be it known that I, HELEN TOMIC, a citizen of Yugoslavia, residing at South Bethlehem, in the county of Northampton and 5 State of Pennsylvania, have invented certain new and useful Improvements in Salvage-Indicating Buoys, of which the following is a specification.

The main object of this invention is to 10 provide a buoy by means of which a sunken ship may indicate its position.

Another object is to provide a salvage indicating buoy adapted to form equipment on ships so that when the latter, for any reason, 15 are sunk, the buoy automatically rises to the surface of the sea and indicates the position of the ship.

A still further object of the invention is to provide an indicating buoy having means 20 thereon which lock said buoy to the deck of the vessel until such time as the deck becomes submerged when the locking means are automatically released by the rising level of the water and permits floating of said buoy.

25 The above and other objects will become apparent in the description below, in which characters of reference refer to like-named parts in the drawing.

Referring briefly to the drawing, Figure 1 30 is a perspective view, illustrating the application of the invention in which the buoys are shown on the surface of the water, marking the position of a sunken vessel.

Figure 2 is a perspective view of the buoy 35 anchor housing.

Figure 3 is a fragmentary side elevational view of the indicating buoy.

Figure 4 is a sectional elevational view 40 thru the buoy, showing the same cooperating with portions of the buoy anchorage housing and illustrating the means for locking said buoy on the housing.

Referring in detail to the drawing, the 45 numeral 10 indicates an ordinary type of vessel which lies submerged upon a reef 11 below the surface 12 of a body of water. The vessel, when afloat, is provided with a buoy anchorage housing at the fore and aft positions. These anchorage housings 50 comprise a box-like frame having parallel side walls 13 and end walls 14 which are joined together to form a square hollow housing, and has a bottom 15 which is securely mounted upon the deck of the vessel, one of 55 each of these housings being provided at the bow and stern. The distance between the

parallel side walls 13 of the housing is spanned by a pair of straps 16 and 17 which are provided with bent downwardly extending feet 18 at their ends, said feet being secured to the interior surfaces of the walls 13 by screws, bolts, or other similar means. The intermediate portions of the bands 16 and 17 are bent in opposite directions to each other to form semi-circular hoops 19 and 20 on which the buoy is supported when normally at rest. These hoops are engaged by cooperating means on the buoy to lock the latter in place on the housing when the vessel equipped with the buoy is afloat.

The buoy consists of a hermetically sealed ball or sphere 21 formed from some relatively light rigid material of suitable strength to withstand rough handling. The chamber 22 contained therein is hermetically sealed, as stated, to create a buoyant body which readily floats and has preferably about half its area exposed above the water level.

At the bottom of the ball, a hollow cylinder 23 is formed which has a hemispherical roof 24 at its upper end and is open at the bottom. Within the bore of the cylinder an inverted cup-shaped plunger 25 is vertically slidable. A stem 26 depends axially from the plunger and its lower end 55 is movable in a chamber formed by an annular sleeve 27 which is integral with the sphere and projects downwardly therefrom and is open at its lower end so that water can rise thereon and actuate the plunger 25. 60 The sleeve 27 is of the same length as the width of the straps and is adapted to snugly slide into the circular space formed by the semi-circular portions of the straps 16 and 17.

On the lower internal periphery of the 65 sleeve at diametrically opposite positions to each other, pairs of ears 28 are formed in which hinge pins are mounted, the latter serving as support pivots for angular bell cranks 29. The arms of the bell cranks 29 extend downwardly and have teeth at their extreme ends which are adapted to engage the underside of the edge of the semi-circular portions 19 and 20 of the straps 16 and 17, and in this manner, lock the buoy or sphere 70 securely seated upon said straps, as indicated in Figure 4. The opposite arms 30 of the bell cranks 29 are in horizontal alignment with each other, extend toward each other, and are connected to the lower end of 75 the stem 26 of the plunger 25 by flexible elements 31. A stud 32 extends diametrically

2 across the lower end of the sleeve 27 and is adapted to have one end of a cable 33 secured and firmly attached thereto. This cable is normally coiled and housed in orderly fashion in the buoy housing and has its lower end firmly anchored to an eye bolt 34 which is mounted on the floor 15 of the housing.

5 A buoy unit is preferably mounted on both the bow and stern of the vessel upon the deck, as illustrated in Figure 1. As a vessel is cruising upon the surface 12 and strikes a reef, shoal, or the like, and has its keel stove in and immediately begins to sink, the buoys 10 become operable as the deck of the vessel submerges below the surface of the water. The vessel, in slowly submerging reaches the level of the bottom of the spherical buoys 15 which are securely locked in place upon the seat formed by the semi-circular portions 20 19 and 20 of the straps 16 and 17 so that the buoy is not tumbled about in rough weather, which would otherwise be the case. The buoy is automatically unlocked from 25 its mooring by the action of the rising water upon the inverted face of the cup-shaped plunger 25. As the vessel slowly sinks, the water rises within the sleeve 27, and as the stem of the plunger 25 is connected to the arms 30 of the bell cranks 29, the latter are 30 rotated so that the teeth on the vertical arms of the bell cranks are disengaged and rotate clear of their contacting engagement with the portions 19 and 20 of the straps, and as 35 the water continues to rise, the buoy 21 is lifted clear of its mooring in the housing and floating of its own accord and remaining on the surface 12 of the water while the remainder of the vessel, including the 40 housing of the buoys, sinks to the bottom. These buoys then act as salvage indicators by which means trawlers or other like vessels can locate the wreck.

45 I claim:—

1. An indicating buoy unit comprising a housing having straps mounted thereon, the

straps being formed into an annular seat, a spherical buoy operated on said seat, a cylinder extending upwardly into the buoy and open at its lower end, means on said buoy for releasably locking the latter in place on the housing, and additional means movable in said cylinder for releasing said locking means when engaged by a rising level of water.

55 2. An indicating buoy unit comprising a housing having straps mounted thereon, the straps being formed into an annular seat, a spherical buoy operated on said seat, a cylinder extending upwardly into the buoy and open at its lower end, a sleeve extending downwardly from said sphere and aligned with said cylinder, toothed bell cranks pivoted in said sleeve diametrically opposite each other and being adapted to normally engage the housing seat, and means operable in said cylinder adapted to rotate the bell crank and actuated by the rising level of water in said cylinder for releasing the bell cranks from engagement with the housing 70 seat.

3. An indicating buoy unit comprising a housing having straps mounted thereon, the straps being formed into an annular seat, a spherical buoy operated on said seat, a cylinder extending upwardly into the buoy operated on said seat, a cylinder extending upwardly into the buoy and open at its lower end, a sleeve extending downwardly from said sphere and aligned with said cylinder, toothed bell cranks pivoted in said sleeve diametrically opposite each other and being adapted to normally engage the housing seat, an inverted cap-shaped plunger slidable in said cylinder, a stem on said plunger connected to said bell cranks, the plunger when lifted by the rising level of liquid being adapted to lift said stem and rotate the bell cranks out of engagement with the housing seat to release the buoy for floating.

90 In testimony whereof I affix my signature.
HELEN TOMIC.
